CANDOLIER

Norman C. Lee, Rocky Mount, N.C., assignor to Carolina Enterprises, Inc., Tarboro, N.C.

Filed July 6, 1970, Ser. No. 23,843

Term of patent 14 years

Int. Cl. D26—05, 01

U.S. Cl. D48—20

FIG. 1

FIG. 2

FIG. 4

FIG. 5

FIG. 1 is a front elevational view of a candelier showing my new design;

FIG. 2 is a top plan view thereof;

FIG. 3 is a side elevational view thereof on a reduced scale;

FIG. 4 is a bottom plan view thereof;

FIGS. 5 and 6 are alternate embodiments of the candelier of my new design.

I claim:

The ornamental design for a candelier, substantially as shown and described.
